PROCESS OF MAKING AMMONIA AND COMPOUNDS THEREOF.

1,207,567.

Specification of Letters Patent.

Patented Dec. 5, 1916.

Application filed September 17, 1913. Serial No. 790,182.

To all whom it may concern:

Be it known that I, HENRY WHITING LAMB, a citizen of the United States, residing at Portsmouth, in the county of Norfolk and State of Virginia, have invented certain new and useful Improvements in Processes of Making Ammonia and Compounds Thereof, of which the following is a specification.

This invention relates to the fixation of atmospheric nitrogen and formation of ammonia, and has for its object the utilization of the varying affinity of solid metal carbid for nitrogen under varying temperatures, for securing nitrogen from its gaseous state and delivering it to hydrogen in the formation of ammonia at thermal points of attraction and expulsion in a progressively alternating and continuous manner, whereby ammonia may be yielded and secured from its elements by the catalytic or contact action of solid metal carbids on free nitrogen and hydrogen actuated by heat broadly, and specifically, by internal heat induced by electrical resistance of the metal carbid to electrical currents and more specifically to electrical currents of varying density, the operation being preferably augmented by exposing the gaseous agents, viz. nitrogen and hydrogen, to chemical change, transformation or union while under super-atmospheric pressure.

In carrying out the process it is preferred to employ an apparatus of the character illustrated in the accompanying drawings to which attention is directed in connection with the description of the various process steps as hereinafter set forth, in which—

Figure 1 is a longitudinal vertical section of a converter adapted to be actuated by electricity, and Fig. 2 is a transverse vertical section in perspective of the same on line 2—2, Fig. 1, Fig. 3 is a side elevation of a modified form of apparatus employing combustion heat, and Fig. 4 is a cross-section on line 4—4, Fig. 3.

Similar numerals of reference indicate corresponding parts in the several views.

Referring to Figs. 1 and 2, the numeral 1 represents a closed metal shell provided with a lining 2. The shell 1 is provided with a cover 3, and heat shield 24, secured thereto by the bolts 4 passing through the flanges 5 in suitable air-tight manner. The interior of the apparatus is provided with an arched or bridged wall 6 provided with perforations or openings 7. At either end of the appa-

ratus shown in Fig. 1, is situated the electrical contacts 8 and 9 communicating with the conductors and electrical attachments 10 and 11. Extending between the said electrical contacts 8 and 9 are graphite rods or conductors of small diameter 12 adapted to act as electrical leads between the points of contact and initial heaters of the metal carbid 13, surrounding the same in the apparatus. On either side of the apparatus is provided a multiplicity or plurality of inlets 14 and 15 communicating with the conduits 16 and 17 and provided with the regulating valves 18 and 19 through which is supplied the nitrogen and hydrogen respectively to the interior of the apparatus in a suitably controlled manner. The apparatus is provided with an outlet 20, provided with an adjustable pressure and relief valve 21, adapted to retain the gases in the apparatus against a fixed and adjustable pressure and to provide for the discharge of the products produced into a suitable conduit 22 communicating with a product reservoir or other means for securing or retaining same (not shown). The apparatus is also provided with a pyrometer 23, by which the internal temperature of the apparatus may be ascertained.

As a concrete example of the process and manner in which the same is performed or carried out, the production of ammonia from atmospheric nitrogen, and hydrogen will be taken.

Calcium carbid, in a pulverized or finely ground condition, is placed in the oven or furnace and is subjected to the alternate action of nitrogen and hydrogen. The carbid composes a contact substance or a catalytic mass which possesses the property of absorbing, combining, retaining or occluding nitrogen or hydrogen when in a heated state, and of delivering the hydrogen or nitrogen to the nitrogen or hydrogen, as the case may be, at a different temperature, at which temperature the carbon has superior affinity for the metal base of the carbid than has the nitrogen or hydrogen. The operation is continued without destroying the physical or chemical character or contact properties of the carbid thereby enabling the carbid to be used repeatedly by merely regenerating the carbid to the active state, alternating the nitrogen and hydrogen, and maintaining the carbid at thermal points where its affinity for nitrogen in-

creases or diminishes while the nitrogen and hydrogen are supplied thereto in the formation of ammonia in the performance of the process.

5 In order to cause the calcium carbid to initially absorb nitrogen, the temperature of the calcium carbid is preferably brought to a point between 1000° C. and 1400° C. where it reverts to the state of a carbid and free nitrogen. However, having once absorbed the nitrogen, it is liberated from the carbid by the hydrogen, in the form of ammonia, at temperatures from 250° C. to 600° C., and the carbid will continue to absorb and to liberate nitrogen and hydrogen at such temperature in the formation of ammonia, as long as the nitrogen and hydrogen are alternately supplied thereto, it being preferable to supply the nitrogen and hydrogen at a pressure of one or more atmospheres. In practice, it is preferable to run the furnace in such a way that the nitrogen and hydrogen are alternately supplied for periods of one hour each, ammonia being 25 liberated continuously.

The nitrogen is preferably recovered from the air or atmosphere by passing it over heated copper or other substance capable of combining with or removing the oxygen 30 while the hydrogen is produced by the de-oxidation of water or steam by the action of heated copper, iron or other metal having superior affinity for oxygen, or with carbon producing water gas from which is eliminated the carbon monoxide or carbon dioxide or both by any well known means. Any other carbid of solid nature than calcium may be employed such as iron, titanium, magnesium, barium, etc., capable of taking 35 on nitrogen and delivering it to hydrogen, either individually or collectively, or the carbid employed may be associated with other solid inert vehicles or carriers for the purpose of rendering available as large a 40 surface to the action of the gases as possible, without departing from the spirit of the invention. The hydrogen employed may be secured from a source foreign to the carbid catalytic substance or can be produced in 45 association therewith by decomposition of water in the presence thereof, in form of steam, superheated steam, or otherwise.

The transformation of nitrogen through the mediation of solid metal carbid into a 50 form or condition nascent in character capable of uniting with hydrogen may be augmented by superatmospheric pressure or carried out under any practical or available condition with reference to the energy employed as to direct heat or induced by electricity as well as under ordinary atmospheric pressure or other conditions.

It will be noted that in cases where electricity is employed as a means for inducing 55 heat through the internal resistance of the

carbid catalytic or contact material that the temperature can be controlled and regulated at will and with great facility and in cases where the material is in granulated form or character the points of contact presenting less cross section of conductive material becomes superheated, or heated to a higher degree than the larger portions of the contacting material through which the current passes whereby in each individual particle 75 a condition may be induced whereby nitrogen may be absorbed at one point and delivered to a hydrogen at another throughout the porous mass simultaneously whereby a mixture of nitrogen and hydrogen may be supplied simultaneously and continuously 80 and the ammonia produced or discharged, instead of supplying the gases alternately and directly altering or changing the temperature of the catalytic or contact metal carbid directly or by or through the means whereby such heat is induced such as electricity.

Referring to the apparatus as illustrated in Figs. 1 and 2 employed in the production of ammonia from nitrogen and hydrogen employing the calcium ferricarbids or its equivalent the operation is carried out as follows: The calcium-iron carbid catalytic or contact substance in a broken or granulated condition is supplied to the apparatus upon the arch support 6 at 13 in such volume as to cover the contact rods or electrical conductors 12 and fill the compartments evenly throughout and at a height of about one-half the distance between the bridge support and the top of the lining 2. The apparatus is then closed by securing the flanges of the cover and furnace by means of the bolts 4. A current of electricity is then passed through the apparatus by means of the leads 12 between the contacts 8 and 9 and through the conductors 10 and 11 whereby the carbid catalytic material becomes heated and when sufficiently hot to admit of the absorption or combination of nitrogen therewith which can be indicated by the pyrometer 23, nitrogen is introduced through the supply pipes 14 by opening the valve 19 which passes into the apparatus and becomes compressed therein passing up through the openings 7 in contact with the carbid 13, until it shall have reached a pressure sufficient to be discharged through the adjusted and weighted relief valve 21. The nitrogen then becomes absorbed by the carbid up to a desired degree of saturation when the current density of the heating current is altered and the nitrogen supply cut off by closing the valves 19. 125 Hydrogen is then admitted through the inlet 15 by opening the valve 18 whereupon the nitrogen is abstracted from the carbid and combined therewith passing out through the discharge conduit 20 to relief 130

valve 21 and conduit 22 to a point where the same is recovered or secured.

Referring to Figs. 3 and 4, the number 25 designates the shell or outside retaining wall of the furnace, provided with the lining 26. The shell 25 is provided with the cover 27 secured thereto by means of bolts 28 passing through the flanges 29, the said cover being provided with openings 30 for the discharge flue 31. Within and passing through the furnace is the retort 32 provided with the heads 33 and 34, respectively. The head 33 being provided with the inlets 35 and 36 controlled by the valves 37 and 38 respectively of nitrogen N and hydrogen H, while the head 34 is provided with outlet 39 controlled by the adjustable relief valve 40 and the conduit 41. The retort 32 is supported on the brick supports 42 in such a manner that the combustible gases may circulate about the retort between the openings 43 between them and these spaces below the retort together with arch space 44 provides a suitable combustion chamber for the combustible gases. On either side of the furnace is provided the inlets 45 and 46 for the combustible gases and air which are supplied through the air supply pipes A and the gas supply pipes G controlled by the respective valves 47 and 48, respectively. The heads of the retort 49 being secured thereto in a removable manner by suitable means such as the screw clamp device 50. The interior of the retort being partly filled with the carbid catalytic agent 51. The combustion chamber 44 is provided with a communicating pyrometer 52 whereby the temperature of the ingredients in retort 32 may be estimated or ascertained. The combustion chamber is provided with a means whereby the combustible gases may be ignited, such as the openings 53 and 54 at either end of the furnace, said openings being provided with the swinging closures 55 and 56, respectively, through which, when opened, a lighted taper or other igniting device may be introduced so as to communicate in an ignitable manner with the combustible gases and air introduced through the supply conduits or pipes 46.

The operation of the combustion heated apparatus is similar to that of the electrically heated. Calcium or other iron carbid is placed in retort 32 at 51 and the heads 33 and 34 closed by the closures 49 actuated by the screw clamp securing device 50. The retort is then heated by means of the combustion of gas entering through the valve controlled gas conduit G mixed with air from supply conduit A and ignited in the furnace through the openings 53 and 54, the combustion in the space 44 about the retort 32 heats the retort and when at the proper temperature, selective to the carbid employed to take on nitrogen which may be

ascertained by the pyrometer 52, nitrogen is introduced into the retort by opening the valves 37 controlling the nitrogen conduit 35 whereupon the nitrogen enters and is absorbed by the carbid. When the carbid has been properly saturated with nitrogen, the supply of nitrogen is cut off by closing valve 37 and the temperature is changed to a point where its affinity is reduced and hydrogen introduced through pipes 36 by opening the valve 38, whereupon the hydrogen seizes the nitrogen forming ammonia and is discharged from the apparatus through the relief valve 40 and conduit 41 and suitably secured therefrom. In some cases as hereinbefore noted, the combustion, or the heating current of electricity may be regulated to such a nicety that the hydrogen and nitrogen may be simultaneously admitted and the ammonia produced, discharged or withdrawn continuously. It is also found advisable in some cases to pre-heat either the nitrogen or hydrogen or both before introduction into the reaction or combining chamber where the cooling action of the gases compared with the volume supplied and the capacity of the apparatus is concerned. When electricity is employed as a means for actuating the heat throughout the body or mass of metal carbid contact material, it may be of alternating, polyphase, direct or other character without departing from the spirit of the invention so long as it coacts with the ingredients to bring about the conditions necessary for the union or combination of nitrogen and hydrogen in the formation of ammonia.

This process is based upon the fact that certain solid metal carbids, such as calcium carbid, iron carbid, and the like, have an affinity for nitrogen when heated and exposed to the action of nitrogen and at certain selective temperatures take on the same forming solid compounds therewith and at certain other temperatures the affinity of the metal base of the carbid for carbon is so changed or intensified that such nitrogen as may be received or absorbed in the first instance may be delivered to a substance capable of combining therewith such as hydrogen and the nitrogen recovered therefrom in nascent form capable of uniting with the hydrogen. The present invention therefore contemplates the utilization of these properties of solid metal carbids for the securing of nitrogen and fixation of the same to and with hydrogen in a progressive or continuous manner and thereby producing a cumulative yield of ammonia which can be absorbed in water, compressed to liquid, combined with other elements, forming compounds, compositions or substitution products, or with acids to form salts or compounds or united in other forms of ammoniacal or azoical compounds or compositions.

The reactions which take place during the employment of calcium iron carbid in the transformation into nitrogen compounds therewith and delivery of the same to hydrogen in the presence of hydrogen may be illustrated by the following chemical formula or equations: The coked mixture or combination of calcium carbid and iron carbid in the preferred proportions employed 10 may be considered as illustrated by the formula Ca_2FeC_6 .

Union of nitrogen:

Formation of ammonia:

20 It will be noted that the solid carbid catalyst is used over and over again with little loss.

The nitrogen may be obtained by passing air over BaO producing barium peroxid BaO_2 by absorbing of oxygen and the oxygen obtained therefrom by reducing the pressure and elevating the temperature thereof by what is known as the "Brin" process and the hydrogen may be supplied 30 as water gas or such hydrogen from which the carbon oxids may have been separated.

The term "containing carbid" employed herein is intended to imply and does imply a carbid as such *per se* or associated with 35 other specific carbids or substances, such for instance as carbon employed as a binder or surface augmenting vehicle or carrier.

The altering of the temperature to augment the seizing of the nitrogen and delivery 40 of the same to hydrogen may be progressively from lower to higher or higher to lower as the case may be with relation to the character of the carbid employed as to whether its affinity for nitrogen increases 45 and decreases in either direction.

It is obvious that when the hydrogen employed is associated with other substances, such as carbon monoxid or carbon dioxid or both, as may be the case in so-called wa- 50 ter gas, that more or less of the ammonia produced will be combined or united in the form of formate or carbonate. The ammonia produced may be combined with acids to form sulfate or chlorid, absorbed in wa- 55 ter, compressed to liquid form or otherwise secured.

The terms "progressive" and "progressively" employed herein in reference to the continuation or carrying on of the process 60 and with reference to steps entering into the change in temperature and the relative change in affinities of ingredients and the character of reacting agents supplied is intended to imply and does imply the con- 65 tinuous carrying on of the various steps em-

ployed during the progress or continuance of the process.

Having now described my invention what I claim as new and desire to secure by Letters Patent, is:—

70

1. The process of making ammonia, which comprises heating solid metal carbid and exposing it to the alternating action of nitrogen and hydrogen during corresponding changes in the affinity of the carbid for 75 nitrogen.

2. The process of making ammonia, which comprises heating solid metal carbid and exposing it to the action of nitrogen and hydrogen under alternately higher and lower 80 temperatures which differ sufficiently to materially vary the affinity of the carbid for nitrogen.

3. The process of making ammonia, which comprises internally heating a substance 85 containing calcium carbid under conditions which alternately vary the affinity of such substance for nitrogen, and exposing it to the alternate action of nitrogen and hydrogen while under superatmospheric pressure. 90

4. The process of making ammonia, which comprises internally heating a substance containing calcium carbid, and exposing it to the action of nitrogen and hydrogen under alternately higher and lower temperatures which differ sufficiently to materially alter the affinity of said substance for nitrogen while under superatmospheric pressure.

5. The process of making ammonia, which comprises heating solid metal carbid and exposing it to the action of nitrogen and hydrogen under temperatures which differ sufficiently to cause a material variation in the affinity of the carbid for nitrogen. 100

6. The process of making ammonia, which comprises heating solid metal carbid and exposing it to the alternating action of nitrogen and hydrogen while under superatmospheric pressure and under conditions which vary the affinity of the carbid for nitrogen. 110

7. The process of making ammonia, which comprises heating solid metal carbid and exposing it to the action of nitrogen and hydrogen under alternately higher and lower temperatures which differ sufficiently to materially vary the affinity of the carbid for nitrogen and while under superatmospheric pressure. 115

8. The process of making ammonia, which comprises internally heating a substance containing calcium carbid, and exposing it to the action of nitrogen and hydrogen under temperatures which differ sufficiently to materially vary the affinity of said substance for nitrogen and under superatmospheric pressure. 120

9. The process of making ammonia, which comprises heating a substance containing calcium carbid until it has reached a temperature at which it has an affinity for ni- 125

5 trogen, supplying nitrogen thereto, altering the temperature of the substance until it has a less affinity for nitrogen, and removing nitrogen from said substance by sub-
jecting the same to the action of hydrogen.

10. The process of making ammonia, which comprises heating solid metal carbid and exposing it to the action of nitrogen and hydrogen under temperatures which vary suffi-
10 ciently to alter the affinity of the carbid for 30 nitrogen and under superatmospheric pressure.

11. The process of making ammonia which comprises heating metal carbid until it has 15 reached a temperature at which it has an affinity for nitrogen, supplying nitrogen thereto, changing the temperature until a temperature is reached at which the carbid has less affinity for nitrogen and has an 20 affinity for hydrogen, removing the nitrogen therefrom by subjecting the ingredients to the action of hydrogen, and removing the hydrogen absorbed or occluded by exposing the substance to the action of nitrogen while 25

at the same temperature at which the substance has an affinity for nitrogen.

12. The process of making ammonia which comprises heating metal carbid until it has reached a temperature at which it has an affinity for nitrogen, supplying nitrogen 30 thereto, changing the temperature until a temperature is reached at which the carbid has less affinity for nitrogen and has an affinity for hydrogen, removing the nitrogen therefrom by subjecting the ingredients to 35 the action of hydrogen, and removing the hydrogen absorbed or occluded by exposing the substance to the action of nitrogen while 40 under superatmospheric pressure.

In testimony whereof, I affix my signature in the presence of two witnesses.
